JACOB MARTIN, OF CAIRO, ILLINOIS.

Letters Patent No. 77,301. dated April 28, 1868.

IMPROVEMENT IN STEAM SLIDE-VALVES.

The Schedule referred to in these Letters Patent and making part of the same.

TO ALL WHOM IT MAY CONCERN:

Be it known that I, JACOB MARTIN, of Cairo, in the county of Alexander, and State of Illinois, have invented a new and useful Improvement in Balanced Slide-Valves; and I do hereby declare that the following is a full, clear, and exact description thereof, which will enable others skilled in the art to make and use the same, reference being had to the accompanying drawings, forming part of this specification, in which—

Figure 1 is a vertical section through the longitudinal axis of a valve and steam-chest made according to my invention, the plane of section being indicated by the letters *y y*, fig. 2.

Figure 2 is a cross-section on the line *x* of fig. 1.

Similar letters of reference indicate like parts.

The object of this improvement is to relieve slide-valves from unnecessary pressure. The valve is quadrangular in shape, its four vertical sides being solid, and its top and bottom being removed, so as to leave its interior open and uncovered, both towards the valve-seat, and also at the back of the valve. The back of the valve is covered by a flat plate, suspended from a piston-rod, whose piston is fitted to a vertical cylinder on the back of the steam-chest. The plate fits steam-tight to the upper face of the valve. The exhaust-steam is passed from the exhaust-port through a pipe leading into the vertical cylinder above its piston, the pipe being continued from the opposite side of the cylinder to a condenser, or other place where the exhaust-steam is disposed of. The top of the suspended plate and the bottom of the piston, which is connected to it by a rod, are exposed to the steam admitted to the chest, and the area of the piston is less than the area of the open back of the valve under the plate, which is there exposed to the exhaust-steam. So much pressure is removed from the valve as is due to the difference in the two areas, which allows the valve to move freely, and with little friction, between the plate and the valve-seat. A very small excess of weight is left on the plate, to make the valve work steam-tight on its two faces. When the exhaust-steam passes through the valve, it has a tendency to raise the plate, but, being conducted through the vertical cylinder above the piston, which is connected to said plate, such exhaust-steam is made thereby to counteract the pressure on the under side of the plate, and to keep the piston and plate in a balanced state.

The letter A designates the place of the cylinder of an engine, and B is its steam-chest, having a slide-valve, C; and valve-stem D. The seat of the valve has induction-ports, H H, communicating with valve-passages E E, which lead into opposite ends of cylinder A. The eduction or exhaust-port F communicates with a port or opening, G, made in the valve-seat midway between the ports H H.

The valve C is quadrangular in form, having its sides and ends vertical. The valve-stem passes through its shorter diameter, being enclosed within a tube which extends between the sides of the valve in that direction. The stem is free to revolve within the tube, and it is connected to the valve by following-nuts, in the usual way. The upper face of the valve is parallel with its lower face, and its back is left open. The open back of the valve is covered by a plate, I, which fits steam-tight to its upper face. This plate is suspended by a rod, N, which carries also a piston, K, fitted in a cylinder, J, which is placed on the top of the steam-chest, and opens therein. The rod N is extended upwards through the cap of cylinder J, and through a stuffing-box, and serves as a guide to the piston and the suspended plate. A spiral spring, L, is placed about the rod N, between the piston and the cap of the cylinder, whose office is to restore the plate I to its proper place in case it is raised off the upper face of the valve by the action of the exhaust-steam.

The exhaust-steam is conducted to the upper part of cylinder J, above the piston K, by a pipe, M, leading from the eduction-port F of the steam-chest, said pipe being continued from the opposite side of the cylinder, to conduct the steam away to its place of final discharge.

In the working of the valve, the exhaust-steam momentarily impairs the vacuum on the eduction or exhaust side of the valve, and has a tendency, by its pressure, to raise the plate from its seat on the upper face of the valve thereon; but such pressure is counteracted by conducting the exhaust-steam from the eduction-port F, through pipe M, into and through the upper part of cylinder J, above the piston K, whereby the piston and plate are kept in a balanced state.

In case of back pressure, the plate will be raised from off the valve; and I have made provision for such an exigency by placing a spring, L, between the piston K and the cap of the cylinder in which the piston is fitted, which spring, by its reaction, insures the return of the plate, and so keeps the valve properly adjusted to its seat when the engine is at rest.

I claim as new, and desire to secure by Letters Patent—

1. The combination of the steam-chest B, exhaust-pipe M, and cylinder J, substantially as herein set forth.
2. I claim the combination of the suspended plate I, piston K, piston-rod N, and spring L, substantially as shown and described.

JACOB MARTIN.
